UNITED STATES PATENT OFFICE.

CARL MUEHLEISEN, OF BALTIMORE, MARYLAND, ASSIGNOR TO THE MERRANTHALER LINOTYPE COMPANY, OF NEW JERSEY.

LINOTYPE-MACHINE.

SPECIFICATION forming part of Letters Patent No. 563,868, dated July 14, 1896.

Application filed April 22, 1896. Serial No. 588,636. (No model.)

To all whom it may concern:

Be it known that I, CARL MUEHLEISEN, of Baltimore, State of Maryland, have invented a new and useful Improvement in Linotype-
5 Machines, of which the following is a specification.

In Mergenthaler linotype-machines, now well-known in the art, a type-metal slug or linotype cast in a mold is driven forward
10 therefrom by an ejector-blade between two trimming-knives, which correct any variation in thickness, into a receiving-galley at the front of the machine. Certain of the machines are adapted to cast slugs which have
15 at one end a two-line letter which overhangs the side of the slug. When these slugs are to be trimmed, it is necessary to withdraw or remove that portion of the trimming-knife which is opposite the overhanging character
20 in order that it may not be sheared from the body of the slug. Heretofore this section of the knife has been withdrawn and held out of action by hand during the passage of each slug with the overhanging ear, and then allowed to return to its former position under the influence of a spring.

The object of my invention is to provide for the mechanical holding back of the retracted knife and its automatic return to its
30 forward position after the passage of the slug.

I have shown my invention in connection with an ordinary Mergenthaler linotype-machine, which, in all other respects, may be of the ordinary construction.

35 Figure 1 is an elevation of the trimming-knives, looking against their inner faces in the direction in which the slug is delivered between them. Fig. 2 is a top plan view showing the knives and their operating devices, the movable knife being in its retracted position. Fig. 3 is a similar view with the movable knife in its forward position. Fig. 4 is a side view of the elevator-frame and its attachment for operating the knife.

45 Referring to Fig. 1, A represents a fixed knife to trim one side of the slug. B B' represents the opposing knife to trim the opposite side of the slug. The lower section of this knife is fixed firmly in position, but the
50 upper section B' is arranged to slide forward and backward. When advanced, as shown

in Figs. 1 and 3, the movable section stands in line with the lower section B, so that the two constitute, jointly, a single knife adapted to dress the slug throughout its length. 55 When, however, a slug with the overhanging ear is presented, the withdrawal of the section B', as indicated in dotted lines, will leave an opening for the passage of the ear above the upper end of the fixed knife B, as plainly 60 shown by the dotted lines. The movable section is guided at its lower edge by a groove in the section B, and the upper edge is guided in a fixed plate C. The adjustment of the movable section is effected by a hand-lever 65 D, pivoted to a bracket E in the main frame, the lever being acted upon by a spiral spring F, which tends to carry the knife to its inner or normal position.

The foregoing parts were invented by another and are not claimed by me. 70

In applying my improvement I connect to the forward end of the knife-adjusting lever D, by a vertical pivot, a horizontal arm G, having at its opposite end a stud or roller H, 75 adapted to be engaged behind a vertical bar or flange I, secured to the vertically-sliding first elevator-frame J, which forms a part of the ordinary machine. When a slug having the overhanging character is to be delivered, 80 the arm G is swung rearward until the roller H will clear the bar I, after which the hand-lever D is thrown to the left, and the arm G is swung forward until the roller H is engaged behind the bar I, as shown in Fig. 2, thus 85 holding the movable knife in its outer or inactive position. In due course of time, and after the slug has been delivered, the movement of the elevator-frame J carries the bar I beyond the roller H, thus releasing the arm 90 G and lever D, so that the spring F returns the knife B' to its forward position.

The essence of my invention resides in combination with the movable knife of means for holding the same in one of its adjusted positions, and means for automatically releasing the same that it may return to its other position. 95

In short, I believe myself to be the first to combine with a movable knife means by 100 which it is automatically moved from one position to another, and it will be manifest to

the skilled mechanic that the form and arrangement of the details may be widely modified within the range of mechanical skill and without passing beyond the limits of my invention.

Having thus described my invention, what I claim is—

1. In a linotype-machine, an adjustable trimming-knife, in combination with mechanism for automatically moving the same from one predetermined position to another.
2. In a linotype-machine, the combination of a movable trimming-knife, a spring tending to hold the same in one position, a latch

mechanism to hold the same in another position, and automatic means for releasing the latch mechanism.

3. In a linotype-machine, the movable knife and its actuating lever and spring, in combination with a latching or holding mechanism for operating with the elevator-slide.

In testimony whereof I hereunto set my hand, this 17th day of April, 1896, in the presence of two attesting witnesses.

CARL MUEHLEISEN.
